BROACHING MACHINE

Francis J. Lapointe, Ann Arbor, Mich.

Application December 16, 1932, Serial No. 647,633

10 Claims. (Cl. 90—33)

My invention has for its object to provide an efficient means for automatically momentarily releasing or cushioning the pressure transmitted from a driving means to a member actuated thereby with the object of preventing a pressure upon the actuated device beyond that normally sustainable thereby. The invention is particularly applicable to machines wherein the elements used to form articles are of a character that for efficient operation should be actuated at a pressure or by a force that is below a certain maximum when performing the function for which the elements are designed, or to prevent their operation under a pressure in excess to that which they can normally stand without risk of injury. The invention thus provides an efficient means for the maintenance of the operation of the elements, such as cutting operations, and prevent breakage where, by reason of their peculiar construction, one or more of their sections are of such a character as to have a relatively small safety factor.

The invention provides a means for limiting the pressure exerted on the machining element to a point below a predetermined maximum and thus operates to automatically protect the element from injury.

The invention also provides an indicator for indicating continuously the changes in pressure required to move the machining element and thereby indicate the change in the condition of element while in use and the condition of the material being operated upon. Thus, by my invention, the condition of a tool, such as a cutting tool, is automatically indicated or an unusual hardness of the material is indicated, as is often found in connection with work on any particular product formed of a plurality of like articles. Indication will be given as to whether the work on the particular article shall progress further or whether the tool should be replaced or resharpened or reformed, or a new tool should be inserted in place of the one that gives indication of lesser efficiency.

The invention thus provides an efficient means for the protection of machine tools and enables rapid production of articles at a great saving of cost by maintaining the tools at their maximum efficiency and preventing breakage of tools that may be more or less complex in character and more or less expensive to make.

The invention consists in other features which will appear from the following description and upon examination of the drawings. Structures containing the invention may partake of different

forms and may be varied in their details and still embody the invention. To illustrate a practical application of the invention, I have selected a broaching machine embodying the invention as an example of the various structures and the details of such structures that contain the invention and shall describe the selected structure hereinafter, it being understood that variations may be made and that certain features of my invention may be used to advantage without a corresponding use of other features of the invention, and without departing from the spirit of the invention. The particular structure selected is shown in the accompanying drawings.

Fig. 1 illustrates a vertical section of the broaching machine selected as an example of the embodiment of the invention. Fig. 2 illustrates a control lever and a side view of a tool elevator for manipulating the broaching tool to enable replacement of the work. Fig. 3 illustrates a front view of the machine. Fig. 4 illustrates a view of a section of the machine showing a rack and pinion that operates the guide plate and the drawhead of the broaching machine. Fig. 5 illustrates a view of a section taken on the plane of the line 5—5 indicated in Fig. 1. Fig. 6 illustrates a view of a section taken on the plane of the line 6—6 indicated in Fig. 5. Fig. 7 illustrates a view of a section taken on the plane of the line 7—7 indicated in Fig. 5 and particularly illustrates valves for controlling the flow of a fluid to and from the drawhead of the broaching machine. Fig. 8 illustrates a broken view of a part of the machine and particularly illustrates switches that are controlled according to the extent of movement of the broaching tool. Fig. 9 illustrates a side view of a cam block used for manipulating the switches.

In the particular form of construction shown in the drawings, a drawhead 1 is connected to a guide plate 2 that is vertically reciprocably mounted in a frame 3 having suitable ways 4 for guiding the plate 2. The plate 2 is reciprocated by means of a rack 5 connected to the plate 2 and a pinion 6 driven by a suitable electric motor 7, through reducing gear, such as the gear wheel 8, the worm 9, a worm wheel 10 which is connected to the shaft 11 to which is keyed, or on which is formed, the pinion 6. These parts are suitably mounted in the frame 3. The worm 9 and worm wheel 10 may be mounted in a suitable gear box or case 12. Suitable switches are provided for controlling the motor 7 to connect and disconnect the motor with the source of supply of electricity to produce the desired reciprocatory

movements of the broach head as guided by the plate 2 and the frame 3 of the machine.

A suitable chuck 16 is connected to the drawhead 1. The chuck 16 is of the type illustrated 5 and described in the Lapointe application No. 517,386, filed February 21, 1931, it being provided with means for engaging the broach when pressure against a spring pressed collar 17 is released. Disengagement with the broach is produced 10 by the descent of the drawhead 1 so as to press the collar 17 of the chuck 16 against the work plate or some part connected therewith. The broach 18 is provided with a broach head 19 that is connected to the body of the broach by 15 means of a neck 20 that is engaged by suitable dogs as described in the said Lapointe application and illustrated, particularly, in Fig. 5.

The drawhead 1 is located above the work plate 21 and, to enable insertion of work below the 20 work plate, the upper end of the broach is positioned well below the work plate. To connect the broach 18 with the drawhead, the broach is raised and inserted through the work and the work plate and into the chuck 16 and held against 25 the drawhead and, when the drawhead 1 is raised so as to relieve the pressure of the work plate against the collar 17, the broach head is engaged in the chuck. Whereupon the broach is pulled through the work by the operation of the pinion 30 6 that meshes with the rack 5 that is connected to the guide plate 2.

As is well known in connection with mechanically operated broach machines, such as the screw or twin screw and nut or the pinion and rack types, 35 the broaches are moved at a uniform speed irrespective of tool resistance, that is, irrespective of the resisting pressure caused by the cutting operation of the teeth. Also, as is well known in broaching operations, the material worked on 40 varies in its characteristics so that in broaching a number of articles of like character there will often be a great variation in the hardness, or elasticity, of portions of the articles. There will be some that will be exceedingly hard where 45 others will be relatively soft and also parts of any one article may be much softer than other parts, hence the broaching tool will be subject to varying cutting resistance in connection with any particular broaching operation. Where uniform 50 movement of the broach is produced, notwithstanding variation in cutting resistance, broaches will be broken or teeth of the broach will be chipped or nicked, or where the hardness differs in the articles of like character being broached, 55 the teeth will dull at varying rates, increasing the cutting resistance at varying rates. Also, where large holes are being cut and large teeth are required to withstand the cutting strain, requiring considerable clearance for chips and con- 60sequently requiring increased distances between the cutting edges of consecutive teeth, there is produced a large variation in the tool resistance as the number of teeth in contact with the surface of the article being cut is varied. Where the 65 teeth are large the cutting resistance may vary as much as 20%, as where four teeth are in contact with the article and a fifth engages, subsequently one of the teeth leaves the article, followed by a tooth entering into or engaging with an article. 70 Also, as is well known in connection with broaching operations, broaches partake of different forms in their cross sections as for cutting slots or square holes or hexes or oblong holes or channels, or undercutting sides of holes or slots, etc. 75 In order to form such slots or openings into their

characteristic shapes, broaches must necessarily be so constructed as to provide teeth having corresponding shapes and provision must be made for clearance and for gathering of the chips within the article from each tooth as it progresses in the article, which results in varying shapes of the shanks or bodies of the broach, particularly the portions located intermediate the teeth. Frequently the cross sectional area of the body of the broach is very slender and of such cross sections as is necessitated by the configuration of the cutting edge and the necessity of provision of clearance and spaces between the teeth for gathering the chips. This frequently necessitates designing broaches within a narrow margin of safety, or 10 with a small safety factor, and while the mechanically operated broach machines are desirable because of their positiveness and uniformity of movement and their speed control, yet for the same reason they fracture broaches because of 20 lack of give or resiliency. Also the practical irres- 25isting forward drive of the broach frequently causes fracture of the heavier broaches by reason of the fact that the spring of the metal of the broaches, when subject to high pressure, causes fracture in the whip back and back lash as the consecutive teeth enter and leave the material. The advantageous features of mechanically driven broaches are retained and the disadvantages eliminated, in my invention, by providing 30 a regulatable cushioning yielding means between the broach and the broach actuating element. 35

The broach being light in weight, or small in mass, it is exactly responsive in its tension to the variation in cutting resistance and when 40 yieldingly connected, as distinct from elastically connected, to the pressure head of the machine, it changes in movement in response to resistance to movement. While the mechanically operated driving member moves at a uniform speed, irre- 45spective to the tool resistance, the invention provides for cushioning the broach in its movement relative to the driving member. This eliminates breaking of the teeth, or fracture of the body of the broach, caused by jarring, or "bumping" of 45 the teeth produced by subjecting one or more of the teeth, within an exceedingly short time, to a pressure that exceeds their elastic limit. The invention provides a means that enables the broach to adjust itself by a momentary diminution of the pressure when it reaches or approximates what may be considered an excess, although the drawhead moves steadily forward re- 50gardless of such changes in pressure.

The invention also provides a means for indicating the cutting resistance to which the broach is subjected whereby increasing dullness, although at varying rates, may be readily noted. Also exceedingly hard articles in any particular product may be quickly noted and the machine 60 stopped, or the characteristic hardness of the articles may be investigated and the articles may be assorted as to their hardness and another broach used for cutting the harder articles or a slower speed used. Thus my invention enables 65 operation of broaching machines at a maximum speed and results in a great saving in cost of operation. By reason of the indicated tool resistance, it enables a very greatly increased 70 broaching rate since it enables speeding up of broaching machines to the maximum safe rate.

In order to obtain these advantageous results in the particular form of construction selected as an example of an embodiment of my invention, the broach 18 is directly connected to a fluid 75

pressed piston 26 by means of the chuck 16 and portions of the fluid are allowed to escape when the pulling pressure exceeds a safe maximum, the cylinder 27 in which the piston is located forming a reservoir of the fluid in an amount sufficient to meet exigencies of cutting resistance variations for which the machine is designed. The escape of the fluid eliminates the reactions of elasticity and the whip-like action caused thereby.

10 The piston rod 25, the piston 26 and the cylinder 27 form a part of the drawhead 1. The cylinder 27 is charged with oil under pressure by means of the pump 28 that is operated by the electric motor 29. The pump 28 is located in the reservoir 30 that operates to force the oil under pressure through the pipes 32 and 33, the passageway 35 formed in the plate 2 and the drawhead 1 to the cylinder 27. The passageway 35 opens into the lower end of the cylinder 27 and beneath the piston 26 and operates to press the piston 26 towards the upper end of the cylinder 27. A suitable engaging screw or stop 36 may be provided in the upper end of the cylinder 27 to adjustably limit the upward movement of the piston 26 and thus limit the oil content of the cylinder and thus limit the slack between the stroke of the broach head and the broach.

When the drawhead 1 is raised by the operation of the pinion 6, the oil located below the piston 26 is subjected to a pressure depending upon the cutting resistance to which the broach 18 is subjected and consequently the piston 26 will give according to the flow of the oil from the cylinder. The piston, however, being subject at all times to a pressure at least equal to that producible by the pump 28 is returned to the upper end of the cylinder and the cylinder charged with a fresh supply of oil upon completion of the working stroke of the broach. The pressure during the working stroke rises well above the pressure that may be produced by the pump 28 by reason of the fact that the oil that passes through the passageway 35 is trapped by means of the one-way spring pressed valve 40. The valve 40 allows substantially free movement of the oil from the pipe 34 into the passageway 35 but operates to prevent any return of oil into the pipe 34 and consequently any counter pressure on the pump 28. Thus by a relative small pump the advantages of my invention may be produced.

The oil may escape from the cylinder only when it reaches a predetermined pressure as determined by an adjustable spring pressed needle valve 43 located in an opening 44 having a small port and formed in a sleeve 45. The sleeve 45 is located in the drawhead 1. The needle valve 43 is provided with a head 46 that is spring pressed by means of the spring 47. The tension of the spring 47 may be adjusted by means of the screw 48 having the knurled head 49. If desired, a nut 50 may be provided for frictionally securing the screw 48 in its adjusted position. The bore 44 is exceedingly small, approximating capillary size and communicates with the passageway 35 that leads to the lower end of the cylinder 27 and the end of the needle 43 is located in proximity to a passageway 51 extending at right angles to the opening 44. The passageway 51 communicates with the passageway 44 when the end of the needle is removed from the passageway 44 and thus allows a very fine stream of oil to escape from the passageway 35 and consequently from the cylinder 27. The opening 44 being practically capillary in size, the amount of escape of oil is very

minute upon each application of excess pressure, that is, pressure in excess of that determined by the pressure of the spring 47. The pressure immediately lowers by reason of the release of this minute quantity of oil which gives opportunity for the broaching tool to adjust itself to the cutting resistance produced by any one of the various circumstances or conditions as to change in number of teeth engaging the article or momentary change in cutting resistance due to local characteristic change in a minute part of the material or due to a fracture of the tooth near the cutting edge or due to momentary failure of delivery of chips from the cutting edges. In other words, it affords a yielding means directly connected to the broach to enable the broach to readily change its speed and yieldingly overcome the resistance to its movement without being subject to any resiliency of the fluid or air in the oil and allow the tool to gradually adjust itself to its own elasticity.

In order to readily control the transmissible pressure between the pressure head and the broach, a pressure indicator 54, of any suitable type, may be connected to the lower end of the cylinder, such as through the passageway 55. The indicator 54 is mounted on the drawhead 1 and indicates the pressure of the oil in the cylinder 27 and consequently the resistance to movement met by the broaching tool. In starting the broaching operation on the product or in using a new broach, the cutting resistance will be noted and the pressure within the cylinder 27 may be promptly varied accordingly by the adjustment of the tension of the spring 47. When a large broach is used the tension of the spring is raised and the variations in the cutting resistance, as the teeth pass over the work, is noted and adjustments made to afford the desired give in the pressure, according to the changes in resistance to movement of the tool, and thus produce the desired protective yield. As the broaching operation progresses, increased dullness of one or more of its teeth is indicated by a gradual increased pressure. Quite sudden though uniform rate of change will indicate increased dullness and decrease in chip delivery from the edges or burnishing of the work at the edges of one or more of its teeth. There will be variations of movement of the indicator by reason of the teeth entering and leaving the work which is noted and allowed for and "bumping" prevented. Marked rise in the indicator will indicate either local hardness of portions of the article being broached or fracture of broach edges which may be immediately determined by examination of the broach and which will require variation either to raise the pressure transmissible to the broach or to allow for decrease of pressure by allowing the escape of oil in slightly increased, though still minute, quantities to increase the give or cushioning effect of the oil. When these conditions are revealed through the indicator, suitable alterations may be made.

The oil that is allowed to escape from the cylinder is returned to the reservoir 30 through the passageway 52 and pipes 53, 56 and 57. The cylinder 27 and the drawhead 1 are provided with a passageway 60 for the discharge of any oil that may accumulate in the upper end of the cylinder to the passageway 52 which is connected to the reservoir. This prevents blocking of the piston when the cylinder is filled. The drawhead is also provided with a passageway 61

which will draw off the oil that passes the packing of the piston rod 25.

The pipes 34 and 53 telescope within the pipes 33 and 56 respectively. Suitable packing glands 5 being provided in the fixture 64 located at the upper ends of the pipes 33 and 56 prevent the escape of oil from the pipes at the telescopic connections. The pipes 34 and 53 are connected to the guide plate 2 and move vertically within 10 the pipes 33 and 56 respectively to maintain the connection of the cylinder 27 with the source of supply of oil under pressure and also with the reservoir 30 as the plate and the drawhead 1 reciprocates in the frame 3.

15 Suitable switches are provided for connecting the motor 7 with the source of supply of electric current and for making the disconnection with the source and for reversing the motor. The switches and circuit controlling devices will 20 vary according to the character of the motor as to whether a direct current motor or an alternating current is used and, if alternating, the switching devices and electric system will vary according to the phases of the current. These 25 features form no part of my invention and provide merely the means for connecting and disconnecting the motor or for reversing the motor. In order that the motor may be disconnected or may be reversed, I have provided switches contained in switch boxes 66 and 67 having arms 68 and 69 that carry rollers 70 and 71. The arms 68 and 69 are connected to suitable switch arms that operate the movable contacts of the switches and when operated they either open or reverse 30 the motor current. The switch contained in the box 66 is operated to open the circuit of the motor by an adjustable cam 73 connected to a block 74, while the switch contained in the box 67 operates to reverse the motor by means of the cam 75 connected to the block 76. The cam 75 operates to raise the roller 71 and swing the arm 69 to reverse the current when the drawhead is raised sufficiently to complete the movement of the teeth of the broach 18 through the work but leaving in the work the pilot 77 to guide it on the return stroke of the drawhead.

The blocks 74 and 76 are adjustably secured in the frame 3 of the machine and particularly in a slot 78 by means of suitable bolts 79 that 50 extend through the slot and clamp the blocks in desired positions to cause reversal of the motor at the desired point in the operation of the broach and to open the circuit of the motor upon completion of the return of the drawhead 1. The 55 switch boxes 66 and 67 are supported on the guide plate 2 and in position to be operated by the cams 73 and 75 located on the frame 3.

When the drawhead returns and presses the collar 17 against the work plate 31, the chuck 16 60 releases the broach head and delivers the broach to a means for lowering the broach to a point well below the work plate to enable insertion of the work intermediate the head of the broach and the work plate. When the work has been placed 65 in position, the broach is then raised to insert its head into the chuck and the motor 7 is started by the operation of a suitable switch which raises the drawhead 1, allows the chuck to engage the broach head and draw the broach through the 70 work.

For manipulating the broach to enable insertion of the work in position and connection of the broach with the drawhead, I have provided an hydraulic means for manipulating the broach. 75 A fixed piston 82 having a hollow stem 83 is con-

nected by means of a pipe 84 to the pipe 32, the valve 85 and the pipe 86. When the valve 85 is operated the cylinder 88 is emptied through the hollow piston rod 83, the pipe 84, the valve 85 and the pipe 87 which is connected to the pipe 57 that leads to the reservoir. The valve 85 may be operated by a suitable pedal lever 89. When, therefore, the broach 18 is to be raised, the lever 89 is depressed and the valve is shifted to connect the pipe 84 with the pump 28 through the pipe 32. This directs the oil under pressure to the upper end of the cylinder through the hollow piston rod 83 and raises the broach 18 to locate the broach head 19 within the chuck of the drawhead. A switch is operated for closing the circuit of the motor and the drawplate and drawhead are raised by the operation of the pinion 6, the pressure in the cylinder 88 causing the broach to follow up the drawhead until the broach is locked in the chuck. The drawhead continues to move up until the working is completed. The motor is then reversed and the drawhead then descends, the cylinder 88 being held up by the pressure of the oil that is inserted in the upper end of the cylinder, while the lever 89 is held down by the operator. When the drawhead reaches the lower point in its travel the chuck is opened and the broach is released and the motor circuit is opened, the operator then releases the lever 89 and allows the escape of oil to the reservoir through the valve 85 and the cylinder 88 together with the broach 18 descends by the weight of the cylinder. If desired, the lever 89 may be released upon locking the broach in the chuck. This permits the immediate return 35 of the cylinder 88, the chuck operating to drop the broach, the lower end entering the socket 91, upon the completion of the return movement of the drawhead.

I claim:

1. In a machine, a drawhead, means for reciprocating the drawhead, a reciprocable machine member, a cylinder and piston for connecting the reciprocable member to the drawhead, means for introducing a fluid into the cylinder and an indicating means for indicating the resistance to movement of the reciprocable machine member, means for maintaining a supply of fluid in the cylinder and means for varying the pressure of the fluid in the cylinder.

2. In a broaching machine, a drawhead, a means for reciprocating the drawhead, a broaching tool, a cylinder and piston for connecting the broaching tool to the drawhead, a source of supply of fluid under pressure, means for connecting the said source of supply with the said cylinder, means for indicating the pressure transmitted through the fluid by the movement of the drawhead when actuating the broaching tool and means for releasing the pressure of the fluid in the cylinder.

3. In a broaching machine, a guide plate, a rack connected to the guide plate, a drawhead connected to the guide plate, a broaching tool, a cylinder and piston for connecting the broaching tool to the drawhead, a source of supply of fluid under pressure, means for connecting the said source of supply with the cylinder, adjustable means for varying the resistance to the return flow of fluid in the cylinder to the source of supply, means for indicating the pressure of the fluid in the cylinder.

4. In a broaching machine, a guide plate, a rack connected to the guide plate, a pinion for

40

45

50

55

60

65

70

75

raising and lowering the rack, a frame, a work plate connected to the frame, a drawhead connected to the guide plate and located above the work-plate, a broach tool, an automatic chuck 5 for engaging the broaching tool for releasing the broaching tool when pressed against the work plate, a cylinder and piston for connecting the chuck to the drawhead, a source of supply of fluid under pressure means for connecting the 10 said source of supply with the cylinder, and means for varying the pressure transmissible through the fluid in the cylinder to the chuck.

5. In a broaching machine, a guide plate, a rack connected to the guide plate, a pinion for 15 raising and lowering the rack, a frame, a work plate connected to the frame, a drawhead connected to the guide plate and located above the work plate, a broaching tool, an automatic chuck for engaging the broaching tool for releasing 20 the broaching tool when pressed against the work plate, a cylinder and piston for connecting the chuck to the drawhead, a source of supply of fluid under pressure, means for connecting the said source of supply with the cylinder, means 25 for varying the pressure transmissible through the fluid in the cylinder to the chuck, and a cylinder and piston for lowering and raising the broaching tool from the chuck when the chuck engages the work plate, and means for connecting the 30 last named cylinder with the source of supply under pressure.

6. In a broaching machine, a draw head means for reciprocating the draw head, the cylinder mounted on the draw head, a piston located in 35 the cylinder, a broaching tool connected to the piston, a source of supply of fluid under pressure connected to the cylinder at a point located on the side of the piston on which the broaching tool is located for transmitting pressure from the 40 draw head to the broaching tool during the working stroke, a pressure indicating means connected to the cylinder on the broach side of the piston, the machine having a passageway connected to the source of supply and to the cylinder 45 on the broach side of the piston, and an adjustable valve, located in the passageway for varying the pressure transmitted from the draw head to the broaching tool.

7. In a broaching machine a pressure head, 50 means for reciprocating the pressure head, a cylinder mounted on the pressure head, a piston located in the cylinder, a broaching tool connected to the piston, a source of supply of fluid, a pressure means for subjecting the fluid to pressure, the machine having a passageway for conducting the fluid under pressure to the cylinder 55 at a point located on one side of the piston, a one way valve located in the passageway for preventing return flow of the fluid to the pressure means, the machine having a return passageway connected to the cylinder on the said one side of the piston and to the source of fluid supply, and a pressure control valve located in the said 60 return passageway and opened by the pressure of the fluid in the said return passageway, a spring for counteracting the fluid pressure on the pressure control valve and normally operating to maintain the control valve closed against the pressure of fluid in the cylinder, and means for adjusting the pressure of the spring to adjust the maximum pressure transmissible from the cylinder to the piston to limit the actuating pressure exerted by the pressure head on the 65 tool during their working strokes.

8. In a broaching machine a pressure head, means for reciprocating the pressure head, a cylinder mounted on the pressure head, a piston located in the cylinder, a broaching tool connected to the piston, a source of supply of fluid, a pressure means for subjecting the fluid to pressure, the machine having a passageway for conducting the fluid under pressure to the cylinder at a point located on one side of the piston, a one way valve located in the passageway for preventing return flow of the fluid to the pressure means, the machine having a return passageway connected to the cylinder on the said one side of the piston and to the source of fluid supply, and a pressure control valve located in the said return passageway and opened by the pressure of the fluid in the said return passageway, a spring for counteracting the fluid pressure on the pressure control valve and normally operating to maintain the control valve closed against the pressure of fluid in the cylinder, means for adjusting the spring for varying the limit of pressure transmissible from the cylinder to the piston, and an adjustable stop located within the cylinder for limiting the movement of the piston relative to the cylinder in a direction away from the said one side of the piston for limiting the slack between the pressure head stroke and the broach movement produced by fluid escapement to the said source of supply of fluid.

9. In a broaching machine, a draw head, means for reciprocating the draw head, a cylinder mounted on the draw head, a piston located in the cylinder, a broaching tool connected to the piston, a source of supply of fluid, a pressure means for subjecting the fluid to pressure, a passageway for conducting the fluid under pressure to the cylinder at a point located on the side of the piston on which the broaching tool is located, a one way valve located in the passageway for preventing return flow of the fluid to the pressure means, the machine having a return passageway connected to the cylinder on the broaching side of the piston and to the source of fluid supply, and a pressure control valve located in the said return passageway, a spring for counteracting the fluid pressure on the control valve and normally operating to maintain the control valve closed against the pressure of fluid in the cylinder, and means for adjusting the pressure of the spring for adjusting the pressure transmissible from the draw head to the broaching tool and limiting the draft pressure on the tool and easing the movement of the tool relative to the draw head.

10. In a broaching machine, a draw head, means for reciprocating the draw head, a cylinder mounted on the draw head, a piston located in the cylinder, a broaching tool connected to the piston, a source of supply of fluid, a pressure means for subjecting the fluid to pressure, a passageway for conducting the fluid under pressure to the cylinder at a point located on the side of the piston on which the broaching tool is located, a one way valve located in the passageway for preventing return flow of the fluid to the pressure means, the machine having a return passageway connected to the cylinder on the broaching side of the piston and to the source of fluid supply and a pressure control valve located in the said return passageway, a spring for counteracting the fluid pressure on the control valve and normally operating to maintain the control valve closed against the pressure of fluid.

in the cylinder, means for adjusting the pressure of the spring for adjusting the maximum pressure transmissible from the drawhead to the broaching tool, and an adjustable stop located within the cylinder for limiting the movement of the piston relative to the cylinder in a direction

in which the broaching tool is drawn by the draw head for limiting the slack between the draw head stroke and the broach movement produced by fluid escapement through the said return passageway.

FRANCIS J. LAPOINTE.
